UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CALCULATING-MACHINE.

1,253,879.

Specification of Letters Patent. Patented Jan. 15, 1918.

Application filed July 20, 1916. Serial No. 110,338.

To all whom it may concern:

Be it known that I, EDGAR E. PHINNEY, a citizen of the United States, resident of New York, in the county of New York and State of New York, have made a certain new and useful Invention in Calculating-Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention.

Fig. 2 is a detail side view of one of the levers carrying the selecting wheels, the operating cam therefor, and adjacents parts.

20 Fig. 3 is a section on the line 3—3, Fig. 2. The invention has relation to calculating machines of the type shown in the reissue patent to Baldwin, 13,841, dated December 8, 1914, and including certain of the modifications thereof shown in the patent to 25 Phinney, No. 1,220,545, dated March 27, 1917. Its object is mainly to provide for continuous rotation of the selecting gears and to reduce the gear ratio, avoiding the knock consequent upon the intermittent 30 starting of the selecting gears and rendering the machine capable of being operated with less effort.

The invention consists in the novel construction and combinations of parts, as hereinafter set forth.

In the accompanying drawings, illustrating the invention, the numeral 1 designates the casing; 2 the transversely shiftable carriage wherein the registering wheels 13 and 35 89 are located; 3 the operating handle; 4 the shaft carrying the selecting or primary wheels 5; 12 the intermediate gears; 18 the depressible keys, and 73 the shaft of the carrying mechanism, bearing the radial arms 40 *m* and the dogs *j*.

Means are provided to move the shaft 4 and the selecting wheels thereon away from the intermediate gears after the selecting wheels have been turned to set up the numbers of the problem upon the intermediate 45 gears, and prior to the effective action of the carrying mechanism, this arrangement allowing for greater compactness of design. Said means consists preferably of levers 15, 50 wherin the shaft 4 is journaled at its ends,

said levers being respectively fulcrumed intermediately of their lengths at 16 to the side plates of the casing and having each an arm provided with outwardly extending branches 17 carrying at their extremities 60 anti-friction rollers 17'; and cams 19, located at the ends of and fast upon the shaft 73 of the carrying mechanism, and against the peripheral surfaces, respectively, of which said rollers bear.

65 In the rotation of the cams, the carrying levers 15 will be rocked first to one side of the normal position shown in full lines, Fig. 2, to move the shaft 4 and the selecting wheels toward the intermediate gears (dotted 70 line position, Fig. 2) and, after the selecting wheels have been turned to set up the numbers of the problem upon the intermediate gears, said levers, shaft and wheels will be reversely rocked, to move said shaft 75 and wheels back to normal position, said levers, the shaft and the wheels being rocked to the other side of normal position, fully out of mesh with the intermediate gears, prior to the operation of the carrying mechanism, and after the carrying has been performed rocked back again to normal.

The driving connection between the operating handle 3 and the shafts 4 and 73 is preferably sprocket gear, being a sprocket 85 chain 20 engaging a sprocket wheel 21 upon the shaft of said handle, a sprocket wheel 22 having the same number of teeth upon the shaft of the carrying mechanism and a sprocket wheel 23 having the same number 90 of teeth upon the shaft of the selecting wheels, an idler sprocket wheel 24 being employed in a bend of the chain, in connection with suitable means 25 for moving said idler wheel to adjust the tension of the chain. 95

The means 25 usually consists of a lever 26, pivoted intermediately of its length at 27 to the side plate of the casing, one arm of said lever having a stud 28 upon which the idler is journaled, an adjusting screw 28' 100 bearing against the other arm of said lever and a spring-pressed block 29 bearing against said screw to hold the adjustment.

In the movement of the selecting wheels into mesh with the intermediate gears and back again to normal position, the sprocket wheel 23 upon the shaft 4 will move therewith, the idler 24 being so spaced as not to interfere.

105 In the operation of the machine, for addi-

tion and multiplication, the handle 3 is rotated once completely to the right, or clockwise. During the first half of this rotation the cams 19 will first bring the selecting wheels into mesh with the intermediate gears, and said wheels will be rotated once completely, to rotate the intermediate gears and thereby the registering wheels to set up the numbers of the problem, and in the second half rotation of said handle the carrying mechanism will be operated, in the usual way, the selecting wheels rotating idly. In subtracting and dividing, the handle 3 is at starting point 3^a, diametrically opposite the starting position 3^b for addition and multiplication, and is moved from point 3^b one complete turn to the left, the operation of the selecting wheels and carrying mechanism being the same as described for the turn to the right. As described in the patent hereinbefore referred to, the operating handle will first be moved one half-turn to the right or left, as the case may be, if necessary, to reach the required starting position.

The idler sprocket wheel 24 is located below the sprocket wheel 23 upon the shaft of the selecting wheels, the driving chain passing in a downwardly extending loop or bend from the wheel 24 to said idler and thence to the wheel 21, so that free movement bodily will be allowed the wheel 23 without interference with the driving engagement of the chain with the wheel 23 or creating slack in the chain.

This idler is also used as stated in adjusting the tension of the chain.

I claim:

1. In a calculating machine, registering wheels, selecting wheels and carrying members actuating the registering wheels, an operating shaft, means for driving said operating shaft, said carrying members and said selecting wheels continuously during the movement of the operating shaft, and means operating in connection therewith for moving the selecting wheels bodily with respect to said registering wheels.

2. In a calculating machine, registering wheels, selecting wheels and carrying members actuating the registering wheels, an operating shaft, means for driving said operating shaft, said carrying members and said selecting wheels continuously during the movement of the operating shaft, and means operating in connection therewith for bodily moving the selecting wheels intermittently toward and away from said registering wheels.

3. In a calculating machine, registering wheels, selecting wheels and carrying members actuating the registering wheels, an operating shaft, means for driving said operating shaft, said carrying members and said selecting wheels continuously during the

movement of the operating shaft, and cam-operated means operating in connection therewith for moving the selecting wheels bodily with respect to the registering wheels.

4. In a calculating machine, registering wheels, selecting wheels and carrying members actuating the registering wheels, an operating shaft, a continuous chain drive connection between said operating shaft, said carrying members and said selecting wheels, and means operating in connection therewith for moving the selecting wheels bodily with respect to the registering wheels.

5. In a calculating machine, registering wheels, intermediate gears, pivoted arms, a shaft mounted therein, selecting wheels upon said shaft, carrying members, said selecting wheels and carrying members adapted to actuate the intermediate gears, an operating shaft, means for driving said operating shaft, said carrying members and said selecting wheels continuously during the movement of the operating shaft, and cam means operating in connection therewith for moving said pivoted arms and the selector shaft and its wheels bodily with respect to the intermediate gears.

6. In a calculating machine, registering wheels, selecting wheels and carrying members actuating the registering wheels, an operating shaft, a continuous drive connection between said operating shaft, said carrying members and said selecting wheels, including sprocket wheels upon the selector shaft, the carrying shaft and upon the operating shaft, an idler sprocket wheel and a chain engaging the sprocket wheels, and means operating in connection therewith for moving the selector shaft and its wheels bodily with respect to the registering wheels, said chain having a bend therein in which said idler is located.

7. In a calculating machine, registering wheels, pivoted arms having branched ends carrying anti-friction rollers, a shaft mounted in said arms, selecting wheels upon said shaft, carrying members, said selecting wheels and carrying members adapted to actuate the registering wheels, an operating shaft, sprocket wheels upon the shafts of the selecting wheels and of the carrying members and upon the operating shaft, a chain engaging the sprocket wheels, and cams upon the shaft of the carrying members engaging said anti-friction rollers to move the selecting wheels bodily with respect to the registering wheels.

8. In a calculating machine, registering wheels, intermediate gears, pivoted arms having branched ends carrying anti-friction rollers, a shaft mounted in said arms, selecting wheels upon said shaft, carrying members, said selecting wheels and carrying

members adapted to actuate the intermediate gears, an operating shaft, sprocket wheels upon the shafts of the selecting wheels and of the carrying members and upon the operating shaft, and an idler sprocket wheel, a chain engaging the sprocket wheels, and cams upon the shaft of the carrying members engaging said anti-friction rollers to move the selecting wheels bodily with respect to the intermediate gears, said chain having a bend therein in which said idler is located.

9. In a calculating machine, registering wheels, selecting wheels and carrying members actuating the registering wheels, an operating shaft, a continuous drive connection between said operating shaft, said carrying members and said selecting wheels, in-

cluding sprocket wheels upon the selector shaft, the carrying shaft and upon the operating shaft, an idler sprocket wheel and a chain engaging the sprocket wheels, means operating in connection therewith for moving the selector shaft and its wheels bodily with respect to the registering wheels, said chain having a bend therein in which said idler is located, and means for moving said idler bodily to adjust the tension of the chain.

In testimony whereof I affix my signature, in presence of two witnesses.

EDGAR E. PHINNEY.
